(57) **CLAIM**

The ornamental design for a foldable paintbrush holder, as
shown and described.

DESCRIPTION

FIG. 1 is a perspective view of a foldable paintbrush holder, which is used for storing or displaying a paintbrush, showing my new design;

FIG. 2 is a reduced front elevational view thereof;

FIG. 3 is a reduced rear elevational view thereof;

FIG. 4 is a reduced left side elevational view thereof;

FIG. 5 is a reduced right side elevational view thereof;

FIG. 6 is a reduced top plan view thereof;

FIG. 7 is a reduced bottom plan view thereof;

FIG. 8 is a front elevational view showing the interior of the
paintbrush holder in an unfolded condition thereof;

FIG. 9 is a front elevational view showing the exterior of the
paintbrush holder in an unfolded condition thereof; and,

FIG. 10 is a right side view of the paintbrush holder in an
unfolded condition.

The broken lines shown in FIGS. 1, 2, 8, and 9 are for
illustrative purposes only and form no part of the claimed
design.
